MICROPHONE CASING

Bruce Kamp, Springfield, Pa., assignor to The Astatic Corporation, Conneaut, Ohio, a corporation of Ohio

Application November 6, 1956, Serial No. 43,682

Term of patent 7 years

(Cl. D26—14)

Figure 1 is a perspective view of a microphone casing, showing my new design;

Figure 2 is a longitudinal cross sectional view of a microphone casing, as shown in Figure 1;

Figure 3 is a side elevation of a microphone casing, as shown in Figure 1; and

Figures 4, 5, 6 and 7 are plan sectional views taken along the section lines 4—4, 5—5, 6—6 and 7—7, respectively, of Figure 3.

I claim:

The ornamental design for a microphone casing, as shown.
